(57) **CLAIM**

The ornamental design for a spa light, as shown and
described.

DESCRIPTION

FIG. 1 is a perspective view of a first embodiment of a spa
light of the present design.

FIG. 2 is a front view of the spa light of FIG. 1.

FIG. 3 is a rear view of the spa light of FIG. 1.

FIG. 4 is a right side view of the spa light of FIG. 1.

FIG. 5 is a left side view of the spa light of FIG. 1.

FIG. 6 is a top view of the spa light of FIG. 1.

FIG. 7 is a bottom view of the spa light of FIG. 1.

FIG. 8 is a perspective view of a second embodiment of a spa
light of the present design.

FIG. 9 is a front view of the spa light of FIG. 8.

FIG. 10 is a rear view of the spa light of FIG. 8.

FIG. 11 is a right side view of the spa light of FIG. 8.

FIG. 12 is a left side view of the spa light of FIG. 8.

FIG. 13 is a top view of the spa light of FIG. 8.

FIG. 14 is a bottom view of the spa light of FIG. 8.

FIG. 15 is a perspective view of a third embodiment of a spa
light of the present design.

FIG. 16 is a front view of the spa light of FIG. 15.

FIG. 17 is a rear view of the spa light of FIG. 15.

FIG. 18 is a right side view of the spa light of FIG. 15.

FIG. 19 is a left side view of the spa light of FIG. 15.

FIG. 20 is a top view of the spa light of FIG. 15; and,

FIG. 21 is a bottom view of the spa light of FIG. 15.

The broken line portions of FIGS. 1, 3-8, 10-15, and 17-21 are
included to show unclaimed subject matter only and form no
part of the claimed design.

1 Claim, 12 Drawing Sheets
